TOOL FOR REMOVING RADIO TUBES AND VIBRATORS

Arthur C. Pothier and Arnold C. Howe,
Portland, Maine

Application June 19, 1947, Serial No. 755,564

7 Claims. (Cl. 254—131)

1

The invention relates to a tool particularly adapted to the removal of radio tubes, vibrators, and similar objects which usually must be removed under very trying conditions.

One of the objects of the invention is to provide a device of this character which will quickly and easily remove radio tubes and the like under most difficult conditions.

Another object of the invention is to provide a device of this character which will quickly and easily remove radio tubes and the like regardless of how limited the working space may be.

A further object of the invention is to provide a device of this character which will quickly and easily remove radio tubes and the like when in highly heated condition during operation, and regardless of the corroded condition of the parts.

Still another object of the invention is to provide a device of this character which will quickly and easily remove even the most fragile glass tubes without any danger of injury to the tube or to the operator.

A further object of the invention is to provide a tool of this character which will quickly and easily remove radio tubes, vibrators and the like, whether such tubes or vibrators are cylindrical throughout or have enlarged portions.

Various other objects and advantages of the invention will be apparent to those skilled in the radio art from the following detailed description, when taken in connection with the accompanying drawings in which:

Figure 1 is a plan view of the tool in combination with a fragmentary representation of any conventional radio;

Figure 2 is a perspective view of the tool positioned to remove a tube;

Figure 3 is a side elevational view of the tool in combination with a tube it has lifted from place; parts of the tool being shown in section to more clearly illustrate the structure; and

Figure 4 is a fragmentary side elevational view of the device, with parts broken away.

The removal of radio tubes, vibrators, etc., has long been a problem. The tubes often have to be removed when in highly heated condition, for example when in operation, and during tests on the production line. But whether hot or cold, tubes are often very difficult to remove because of corrosion of the parts. Then too, the space within which the tool can operate is usually extremely limited, and most tubes are of fragile glass.

Prior to the present invention no tool has been devised which will quickly and easily remove

tubes under the difficult conditions mentioned above, and particularly fragile glass tubes. It will be understood that in the use of the word "tube" herein and in the claims or elsewhere, it is intended to include not only radio tubes used in home sets, automobile sets, aviation sets, radar, etc., but also vibrators and such devices used in such sets.

Referring now to the drawings, numeral 1 indicates a lever in the form of a hand grip, and numeral 2 indicates a lower fixed hand grip; these parts to be gripped by the hand in operation; the forward ends of the hand grips being hingedly connected to a link 3.

15 Soldered, welded, or otherwise rigidly attached to and depending from the lower hand grip 2 is a relatively long, slender tubular member or sleeve 4. Numeral 5 indicates a foot which is welded to or integral with the lower end of the tubular member. And housed within this tubular member is a spindle or plunger 6, which preferably has a pointed lower end 7. This pointed lower end makes a minute indentation in the floor of the chassis, in the operation of the tool, 20 and thus prevents any slippage, and avoids the necessity of any pre-arranged construction of the chassis floor to hold the tool against slippage. And it will also be noted that as the lower portion of the spindle and its pointed end are entirely housed within the sleeve 4, until the tool is 25 actually operated to lift the tube, there is nothing to prevent the foot from being quickly arranged in the desired position for tube removal which, obviously, would not be the case if the lower end 30 of the spindle and the pointed end projected from the foot during the positioning of the foot.

The lever 1 and handle 2 are shown as hollow, and the lower side of the lever 1 is provided with an opening 8 to receive the upper end portion 9 of the spindle or plunger 6. The diameter of the opening 8 is slightly greater than the diameter of the upper end portion 9 of the spindle, so as to permit free swinging movement of the lever about the upper end of the spindle, as best 45 shown in Figure 4.

The upper end portion 9 of the spindle has a slightly smaller diameter than the remainder of the spindle, to form a shoulder 10, and sweated or otherwise secured to the spindle portion 9, 50 and abutting the shoulder 10, is a pressure bead or flange member 11, which may have its upper surface frusto-conical in shape. Mounted on the spindle, between the upper side of the hand grip 2 and the lower side of the bead 11, is a coil 55 spring 12.

In connection with the detailed construction described immediately above, and best shown in Figure 4, it will be noted that the coil spring normally forces the spindle 6 and the lever 1 upwardly, so that the lower end of the spindle is normally housed within the sleeve 4. And that the free upward movement of these parts is limited by the wall of the opening 8 contacting with the portion 9 of the spindle, in the upward swinging movement of the lever. It will also be noted that to remove the spindle and spring, for repair or replacement, it is only necessary to compress the spring by finger pressure on the bead 11, whereupon the lever 1 can be thrown entirely clear of the spindle, so that the spindle and spring can be removed. The parts are assembled in the reverse manner; the spindle being inserted in the sleeve, with the spring mounted thereon between the upper side of the handle 2 and the lower side of the bead 11, and then the spindle is pressed downwardly by finger pressure to compress the spring, and the lever 1 is then swung over so that the upper end 9 of the spindle will enter the hole 8. The parts are then released, whereby the spring will cause the parts to snap to the position shown in Figure 4, ready for use.

Numeral 13 refers to a radio tube which may be of any desired type, and the tube may be entirely of glass, or of glass with a metal base, or of any other material of which radio tubes are made. And, of course, the tube may be mounted in position by any of the well known means. In the specific form illustrated the tube is of glass with a metal base 14, and the base is provided with a depending centrally arranged plug 15, around which are a plurality of depending fingers 16. In mounting the tube in operative position the plug 15 and fingers 16 are inserted in appropriate openings 17 and 18, respectively, as is well known.

While the tubes are easily inserted in a set, it is often most difficult to remove them, because of the small space in which a tool can operate, and it is particularly difficult when the parts have become corroded, with resulting verdigris deposits, etc. And the problem of removal is aggravated, of course, when the tubes must be removed when highly heated, as is often the case.

The operation of the present invention in removing tubes, vibrators, etc., is extremely simple. The handle 2 is always in fixed position relative to the depending tubular member or sleeve 4; these two parts preferably being arranged at right angles, as clearly shown in the drawings. When the operator takes the device in his hand, the horizontal handle 2 rests on his fingers, and the sleeve 4 projects downwardly through his fingers. In the specific embodiment illustrated the relatively long depending sleeve 4 and spindle 6 normally hang vertically downward when the device is resting freely on the fingers, with the hand lever 1 inclined upwardly in the same vertical plane, and of course the lower end of the spindle is housed within the sleeve.

So to remove a tube it is only necessary to lower the hand until the foot 5 strikes the floor or base 19 of the chassis, and then force the foot under the bottom of the tube; the position of the various parts now being as illustrated in Figure 2. In some cases it is necessary to tip a tube slightly for the insertion of the foot 5.

The parts being in position shown in Figure 2, to remove the tube it is only necessary to press down with the hand on the lever 1 to move it

about the upper end of the spindle; the bead 11 acting as a fulcrum for the lever. This leverage movement lifts the tubular member with its foot 5, as the tubular member is fixed to the hand grip 2 which is connected to the lever by the link 3. Of course the pointed end of the spindle 6 remains in engagement with the floor 19 of the chassis. This action results in lifting the tube vertically; its removal being easy, quick and certain. It should be mentioned at this point that when the device is operated to remove a tube, it is usually necessary to press a finger of the other hand against the opposite upper end of the tube to maintain it in substantially vertical position during removal. The position of the parts when the device has been operated to remove a tube is shown in Figure 3.

The device is now released, whereupon the spring 12 forces the lever 1 away from the grip 2, to thereby draw the lower end of the spindle 6 within the tubular member 4; the movement of the lever 1 being limited by the wall of the opening 8 engaging the upper end portion 9 of the spindle.

In connection with the operation of the tool, attention is called particularly to the shape of the foot 5 relative to the tubular member or sleeve 4. The drawings illustrate the tool in use with tubes or vibrators which are cylindrical in shape. And by reference to the drawings, particularly in Figures 2 and 3, it will be noted that when the tool is in vertical position the foot inclines slightly downwardly from the tubular member 4, so that the foot is readily inserted beneath the tube or vibrator.

However, radio tubes, vibrators, and the like are often made of such shape that an upper portion thereof is of greater diameter than the lower portion or base. The present invention is particularly adapted to the removal of tubes and the like of such shapes. As mentioned hereinbefore the foot 5 inclines slightly downwardly from the sleeve 4, and thus the tool may be inclined to the vertical, to clear any enlarged part of the tube or the like, and foot 5 will be flat upon the floor of the chassis, in proper position to be inserted for the removal operation.

This is best understood by reference to Figure 3. Let it be assumed that the parts in that figure are shown prior to the operation of the tool to lift the tube. The tool is in vertical position and the foot is inclined downwardly so that its toe rests on the floor of the chassis, ready to be inserted beneath the tube, which is shown in this instance as of the cylindrical type. But suppose the tube is bulged or flared or of any shape having an upper portion of greater diameter than the lower portion or base. In that event it is only necessary to incline the tool slightly outward from the vertical position shown, as far as necessary to clear the enlarged part of the tube, or until the entire foot rests upon the chassis floor, whereupon the toe still remains in position to be inserted beneath the tube. Thus it is clear that even in the restricted spaces within which the tool operates, it is particularly designed to remove tubes and the like regardless of the shape thereof.

From the foregoing description it will be apparent that we have devised a very simple and inexpensive tool which greatly facilitates the removal of tubes, vibrators and the like, however limited the working space may be, and regardless of the corroded condition of the parts or the

heated condition of the tube or the fragility thereof.

Having fully described the invention, what we claim is:

1. A tool for removing radio tubes including a slender tubular member adapted to be inserted within restricted spaces in a set, a foot on the lower end of the tubular member and extending laterally therefrom, said foot shaped to engage under a tube, a spindle housed within the tubular member and adapted to engage the floor of a chassis, the upper end of the spindle extending beyond the tubular member, a hand grip rigidly fixed to the upper portion of the tubular member, and a hand lever pivotally mounted relative to the hand grip, said hand lever having one end operatively connected with the hand grip to lift the hand grip and attached tubular member to remove a tube when the other end of said lever is pressed downwardly.

2. A tool for removing radio tubes including a long slender member adapted to be inserted within restricted spaces in a set, a foot on the lower end of said member to engage under a tube, a spindle associated with said member and adapted to engage the floor of a chassis, the upper end of the spindle extending beyond the upper end of said member, a hand grip rigidly attached to the upper portion of said member, a bead or flange adjacent the upper end of the spindle, a coil spring on the upper portion of the spindle between said hand grip and said bead or flange, and a hand lever engaging said bead or flange, relative movement of the hand lever and hand grip causing upward movement of said member to remove a tube.

3. A tool for removing radio tubes including a long slender member adapted to be inserted within restricted spaces in a set, a foot on the lower end of said member to engage under a tube, a spindle associated with said member and adapted to engage the floor of a chassis, the upper end of the spindle extending beyond the upper end of said member, a hand grip rigidly attached to the upper portion of said member, a bead adjacent the upper end of the spindle, a coil spring on the upper portion of the spindle between said hand grip and said bead, a hand lever engaging said bead, and a portion of said spindle above the bead engaging an opening in the hand lever, relative movement of the hand grip and hand lever causing upward movement of said member to remove a tube.

4. A tool for removing radio tubes including a slender tubular member adapted to be inserted within restricted spaces in a set, a foot on the lower end of said member to engage under a tube, a spindle housed within said tubular member and adapted to engage the floor of a chassis, the upper end of the spindle extending beyond the upper end of the tubular member, a hand grip rigidly attached to the upper portion of the tubular member, a bead adjacent the upper end

of the spindle, a coil spring on the upper portion of the spindle between said hand grip and said bead, a hand lever engaging the bead, the hand grip and hand lever being pivotally connected, the hand lever having an opening extending through its lower side, and a portion of said spindle above the bead extending through said opening, relative movement of the hand lever and hand grip causing upward movement of the tubular member to remove a tube.

5. A tool for removing radio tubes including a slender tubular member adapted to be inserted within restricted spaces in a set, a foot extending laterally from the lower end of the tubular member and shaped to engage under a tube, said foot inclined slightly downwardly from said member whereby the toe of the foot will be so positioned as to engage under a tube whether said member is in vertical position or inclined away from the tube to be removed, a spindle housed within the tubular member and adapted to engage the floor of the chassis, and a hand lever operable to lift the tubular member to remove a tube.

25 6. A tool for removing radio tubes including a slender tubular member adapted to be inserted within restricted spaces in a set, a foot at the lower end of the tubular member and extending laterally therefrom, said foot shaped to engage under a tube, a spindle housed within the tubular member and adapted to engage the floor of the chassis, the lower end of the spindle being pointed to cause in operation a minute indentation in the chassis floor to prevent slipping, and 30 a hand lever operable to lift the tubular member to remove a tube.

7. A tool for removing radio tubes including a slender tubular member adapted to be inserted within restricted spaces in a set, a foot at the lower end of the tubular member and extending laterally therefrom, said foot shaped to engage under a tube, a spindle mounted within the tubular member and adapted to engage the floor of the chassis, the lower end of the spindle being pointed, a spring causing the lower portion of the spindle to be normally housed in the tubular member, and a hand lever operable to lift the tubular member to remove a tube.
